(57) **CLAIM**

The ornamental design for a liquid chromatography apparatus, as shown and described.

DESCRIPTION

FIG. 1 is a front view of a liquid chromatography apparatus showing a first embodiment of our new design;
FIG. 2 is a rear view of the first embodiment;
FIG. 3 is a left side view of the first embodiment;
FIG. 4 is a right side view of the first embodiment;
FIG. 5 is a top view of the first embodiment;
FIG. 6 is a bottom view of the first embodiment;
FIG. 7 is a front view of a second embodiment;
FIG. 8 is a rear view of the second embodiment;
FIG. 9 is a left side view of the second embodiment;
FIG. 10 is a right side view of the second embodiment;
FIG. 11 is a top view of the second embodiment; and,
FIG. 12 is a bottom view of the second embodiment.
The second embodiment is similar to the first embodiment, but has one more unit located between the units.
